(57) CLAIM

The ornamental design for a triptych banner assembly, as shown and described.

DESCRIPTION

The disclosure of related U.S. Design Application No. 29/182,339, filed May 27, 2003 is herein incorporated by reference in its entirety.

FIG. 1 is a front view of a triptych banner assembly, including left, right, and center sections;

FIG. 2 is a front view of the left section shown removed from the triptych for clarity of disclosure, the right section being identical to the left section;

FIG. 3 is a perspective view of the left section shown removed from the triptych for clarity of disclosure, the right section being identical to the left section;

FIG. 4 is a right-side view of the left section shown removed from the triptych for clarity of disclosure, the right section being identical to the left section;

FIG. 5 is a left-side view of the left section shown removed from the triptych for clarity of disclosure, the right section being identical to the left section;

FIG. 6 is a rear view of the left section shown removed from the triptych for clarity of disclosure, the right section being identical to the left section;

FIG. 7 is a top view of the left section shown removed from the triptych for clarity of disclosure, the right section being identical to the left section; and,

FIG. 8 is a bottom view of the left section shown removed from the triptych for clarity of disclosure, the right section being identical to the left section.

The broken lines represent environmental structure and form no part of the claimed design.
